(57) **CLAIM**

The ornamental design for a handle for plumbing fitting, as
shown and described.

DESCRIPTION

FIG. 1 is a right, top, front perspective view according to my
new design of a handle for a plumbing fitting, such as a hand
shower having a shower head as shown in phantom;

FIG. 2 is a front elevational view thereof, the left side, right
side and rear elevational views thereof being identical to the
front view shown;

FIG. 3 is a top plan view thereof; and,

FIG. 4 is a bottom plan view thereof.

The broken line representations of hand shower environment
in FIGS. 1, 2 and 4 and of an opening in FIGS. 1 and 3 are
for the purpose of illustration only, and form no part of the
claimed design.
